FONT OF NUMERALS

Norman R. Howes, Dallas, Tex., assignor to Texas Instruments Incorporated, Dallas, Tex.

Filed Aug. 6, 1971, Ser. No. 176,379

Term of patent 14 years

Int. Cl. D18—03

U.S. Cl. D64—12 B

FIG. 1 is a face view of a font of numerals showing my design;

FIG. 2 is a face view of another embodiment of part of the font of numerals shown in FIG. 1;

FIG. 3 is a face view of still another embodiment thereof;

FIG. 4 is a face view of a further embodiment thereof; and

FIG. 5 is a face view of a still further embodiment thereof.

I claim:

The ornamental design for a font of numerals, as shown and described.
